UNITED STATES PATENT OFFICE.

CHARLES E. GODLEY, OF DETROIT, MICHIGAN, ASSIGNOR TO EDMUNDS & JONES CORPORATION, OF DETROIT, MICHIGAN, A CORPORATION OF NEW YORK.

COMBINATION TAIL LAMP.

Application filed June 13, 1924. Serial No. 719,916.

My invention relates to compartmental lamps in which a separately controlled source of light (such as an incandescent lamp) is employed for each compartment, 5 and in its general aspects aims to provide features of construction which will permit the use of unusually large lamp bulbs and lenses in proportion to the size of the compartments, which will lend itself to the use 10 of easily manufactured partitioning means and socket constructions, and which will afford advantageous means for holding the translucent elements of the casing and the signal displaying stencil in secure and prop- 15 erly cushioned operative position.

Where lamps having separate sources of light in two compartments are employed for such purposes as the affording of a tail light and a stop signal at the rear of an automobile, it is highly desirable to have the casing of a relatively small size, this being advantageous both to reduce the cost and to avoid clumsiness of appearance. However, 20 adequate room must be provided for the ready insertion of the needed incandescent lamp bulbs, and the insertion or removal of each lamp bulb should desirably be permitted without detaching any portion of the lamp excepting the usual lens-carrying 25 cover. On the other hand, a proportioning of the compartments with respect to the size of the lamps which are to be inserted in them may not have these compartments correspond to the desirable relative sizes and 30 shapes of the lens portions (or separate lenses) which are to be employed with them.

For example, in providing such an automobile lamp with a stop signal portion disposed above the usual tail light indication, 40 both of the lens portions can readily be displayed in an adequate size within a circular cover of relatively small diameter by making the lower lens portion of an oval shape and the upper one of an arcuate 45 shape, with its lower edge curved similarly to the contour of the upper portion of the oval lens portion. Such a relatively long and narrow arcuate shape readily lends itself to displaying a legend such as the word 50 "Stop" even when of less height than the oval lens portion employed for the tail signal which is continuously lighted at night. However, the effective displaying of the stop signal in such close association with the

continuously illuminated tail indication de- 55mands a much more intense lighting of the stop signal lens in order to have the latter attract due and immediate attention. Consequently, a lamp bulb of larger size and candle power than the one employed for the 60 tail light portion of the lamp is desirable for the stop signal indication, but such a larger size of lamp bulb cannot readily be inserted in a compartment corresponding in 65 maximum height to the height of such an arcuate stop lens portion.

In one of its important aspects, my invention aims to overcome these difficulties by providing a partitioning arrangement for the lamp which will permit the socketing 70 portion for the larger lamp bulb to be disposed on the opposite side of the partition from the filament of that bulb, which will permit the attaching of the incandescent lamp from the side of the partition on which 75 the bulb is to be disposed, which will hold the lamp bulb in rigid position transversely of the partition, and which will prevent an overstraining of the contact member associated with the axial terminal of the lamp 80 bulb. It also provides a partition construction which will enable the light from the lamp bulb at one side of the partition to reach all of the outwardly exposed portions 85 of a lens extending beyond the general plane of the partition.

In another aspect, my invention provides a simple and effective cushioning and mounting for the lens portions of such a lamp, including simple and effective means 90 for holding the signal-indicating stencil plate in position and for pressing this plate firmly against the back of the corresponding lens portion without employing any screws other than those required for fastening the 95 lens-carrying cover to the body of the lamp. Furthermore, my invention provides a novel and effective cushioning and supporting arrangement for the glass pane of a bottom window in the lamp through which light 100 from the lamp bulb employed with the tail signal can also illuminate the usual license plate. My invention also provides a novel lens formation for the bottom or license plate illuminating window pane of the lamp 105 and employs lens-forming portions of this window pane both for retaining the latter in its normal position, for preventing the

2 back portion of the partitioning member from being flexed out of its normal position, and for preventing the packing frame associated with this bottom window pane 5 from being forced down into or through the bottom opening in the casing when this pane is clamped in position. Still further and also more detailed objects of my invention will appear from the following specification 10 and from the accompanying drawings, in which—

Fig. 1 is a central, vertical and longitudinal section through a combined stop and tail lamp embodying my invention.

15 Fig. 2 is an elevation of the same lamp taken from the mouth thereof with the cover detached, certain portions being broken away to show the arrangement employed for supporting and cushioning the glass window 20 through which light is directed towards the rear license plate as usually mounted below such a lamp.

Fig. 3 is a central and vertical section through the cover as it appears when detached from the lamp body.

Fig. 4 is a rear elevation of this cover as it appears when detached from the lamp body.

Fig. 5 is a perspective view of the partitioning member of the lamp, showing this with the shell of the lower socket already attached to it.

Fig. 6 is a front view of the metal cover portion alone.

35 Fig. 7 is an enlarged section taken transversely of the lamp through a lower portion thereof to show the method of cushioning the lower glass window pane and the clamping of this pane by means of clips.

40 Fig. 8 is an elevation of the packing member of the lamp front.

Fig. 9 is an enlarged central and vertical section through the lower socket, showing the circuit connections.

45 Fig. 10 is a fragmentary horizontal section taken along the line 10—10 of Fig. 2 and showing the means for securing the lamp front to the partitioning member.

50 Fig. 11 is a section similar to Fig. 3 but showing the use of two separate lenses.

In one of its immediate commercial aspects, the lamp of my invention is particularly adapted for use with rear lights for automobiles. I am therefore illustrating and describing it in such an embodiment, although I do not wish to be limited to this particular employment of the novel features here disclosed. In the illustrated embodiment, the lamp body has a cylindrical wall 1 55 extending forwardly of the lamp (or towards the mouth of the lamp body) from a flat back 2, which back carries rearwardly projecting bolts 3 for attaching the lamp to any suitable support. The cylindrical wall 1 has its forward end enlarged to afford an

outwardly directed flange adapted to act as a seat for certain of the lamp front elements as hereafter described.

Extending across the lamp body is a partitioning member which in this embodiment 70 comprises a pair of portions 5 extending in the same horizontal plane from each side of the lamp body for some distance towards the axis of the lamp, these horizontal portions being connected by downwardly sloping portions 6 to a lower medial portion 7 which also has its main part in a horizontal plane. This lower medial portion 7 has a perforation 48 of a diameter slightly larger than that of the usual base 8 of the incandescent lamp bulb 39 which is to be used for lighting the upper compartment and for projecting light through the signal lens portion 9 in front of this compartment. The lower partition portion 7 also has a pair of 80 downwardly directed wings 10 formed from it at diametrically opposite sides of the perforations 48, each of which wings is provided with a bayonet slot 53 adapted to engage one of the usual anchoring pins 11 on the base 8 of the upper lamp bulb. Both of these bayonet slots 53 have entrance openings at the top of the lowered partition portion 7 as shown in Fig. 5, but are closed downwardly so as to limit the downward movement of the lamp when this is being inserted, thereby preventing the resilient contact arm 23 from being overstrained.

The partitioning member also includes a pair of lugs 12 having perforations for receiving screws 13 by means of which the partitioning member is secured to the back 2 of the lamp body, and has at its forward edge a pair of lugs 14 provided with threaded perforations for receiving the screws 38 by means of which the lamp front is secured to the partition and thereby held in place with respect to the lamp body after the manner shown in Fig. 10.

As illustrated, the partitioning member also includes a downwardly directed web 15 provided at its lower end with a forwardly projecting flange 16 adapted to engage the rear edge of the glass window pane 17 through which light from the lower lamp bulb 18 is directed downwardly toward the rear license plate above which such a combination lamp is usually mounted. This web 15 has a perforation bordered by a rearwardly extending flange 19, which flange is here shown as telescoped into a corresponding rearwardly directed flange 20 on the back 2 of the lamp body. Extending through the inner flange 19 is the metal shell 21 of a lamp socket which is equipped at its rear end with bayonet slots 22 for receiving a double pole connector plug which has its two poles respectively connected to circuit wires for the tail lamp 18 and the stop signal lamp 39. This socket is here shown as

constructed after the general manner shown in application No. 653,106, of Edward S. Preston as interconnected lamp sockets as filed July 23, 1923, namely with one connector plug terminal connected through a compressible conducting member 43 with the axial contact of the lower lamp bulb 18, while the other plug terminal 41 is connected through a compressible conducting member 49 with the lower end of a contact member 23 which has a resilient upper end portion disposed for engaging the axial contact of the upper lamp bulb 39, the latter having the anchoring pins 11 on its base interlocked with the bayonet slots in the said lower wings 10 on the partitioning member.

For the lamp front member I desirably provide a metal cover 50 having a flange 24 adapted to be sleeved over the rim of the radial flange 4 at the mouth of the lamp body, this cover having an upper arcuate perforation, a lower oval perforation and a pair of screw holes 25 adapted to align with the perforations in the front attaching wings 14 of the partitioning member. Seated within this cover is a lens member. When both lens members are to be of the same color, they may be formed of a single piece of suitably colored glass having a lower oval lens portion 10 convexed forwardly and projecting through the lower oval perforation beyond the metal portion of the lamp front, and having an upper flat glass portion disposed behind the said arcuate perforation.

By disposing the upper or signal lens portion in an arcuate formation above a lower oval lens portion, I can readily provide two such lens portions of adequate size in a cover of relatively small diameter, and by lowering the medial socket-carrying part of the partition I can employ an upper lamp bulb of considerably greater length than the distance from the top of the oval lens portion 10 to the top of the lamp body. However, such an arrangement disposes the lowered partition portion 7 in a plane intersecting the oval lens portion and hence would prevent light rays of the lower lamp bulb from reaching the upper portion of this lens. To avoid this, I bow the partition portion 7 upwardly at its forward end to form a forwardly and upwardly flaring reflector portion 26, thereby permitting light from the filament of the lamp 18 to reach the full effective height of the lower lens portion 10. Then I also desirably shape the upper edge of this inclined reflector portion 26 so that it corresponds substantially to the contour of the upper exposed portion of the oval lens 10, thereby causing this reflector portion to redirect some of the light from the lamp 18 in a substantially horizontal direction through the said lens, so as to increase the luminous effect of the upper part of the lens forwardly. Consequently, since the down-

and to compensate for the difference in the distance from the lamp to the upper and lower parts of this lens.

To hold the lower curved glass pane 17 effectively in position and to seal this window opening, I desirably provide a frame 27 of packing material between the lower edge portions of this glass and the adjacent wall of the casing. Then I bevel the two ends of this glass and hold both the glass and the packing in effective position by means of a pair of metal clips 28, each of which is held in position by a screw 29 extending through the cylindrical wall portion of the casing. Each of these clips has a main portion 28 extending in the same general direction with the adjacent portion of the casing, a holding finger 31 disposed at one end of this main portion and inclined to conform substantially to the bevel of the adjacent pane end, and a foot 30 at the other end of the clip for spacing the said main portion from the adjacent casing wall. Owing to the corresponding inclination of the end bevels and the finger engaging these, each finger exerts a cam action to draw the pane towards the adjacent casing wall when the screw 29 is tightened, thereby firmly clamping the packing 27 between the casing and the glass pane. By providing a little lost play in the casing wall perforation through which each screw 29 extends, I can readily cause the corresponding clip to adjust itself to any variation in the precise length of the glass window, thereby holding the latter firmly in its closure position without overstraining it, and by keeping the clip clear of the packing I clamp the latter in proper cushioning and sealing disposition between the glass pane and the casing.

The bottom pane 17 preferably has its central portion thickened and extending downwardly through the opening in the packing frame, and the lower face of this pane desirably has a convexed cylindrical surface of smaller radius than the upper surface of this pane, thereby providing a lens formation for concentrating the downward light from the lower lamp bulb upon a license plate which is disposed below the lamp after the usual custom. This thickened central portion of the pane desirably corresponds in width to the opening in the packing frame, so as to afford two walls engaging the inner edges of the packing frame which extend transversely of the lamp and hence preventing even a thin packing frame from being squeezed down into or through the said bottom opening when the lower window pane is clamped in position.

So also, the front edge of the thickened pane portion is disposed for engaging the front edge of the bottom opening in the casing to prevent the pane from being slid

wardly extending part 15 of the partitioning member has a flange 16 disposed for engaging the rear edge of the said pane, a forward thrust on this part 15 (such as may occur when a wire terminal plug is being inserted in the socket shell 22) cannot flex this part 15 out of its normal position. Hence I am able to use thin metal for the partitioning member without requiring auxiliary means for securing this lower part 15 to the back of the lamp casing.

To display the desired legend by means of the upper lamp portion I desirably employ a metal stencil plate 32 having perforations 33 formed therein to display the desired lettering. Then I fasten this stencil plate to the front portion of the lamp front 24 by a pair of eyelets 35 which extend successively through the said metal front, the glass lens plate, the frontal packing member 35, and the stencil plate 32. With this in mind I provide a packing member 34 in the form of a disk of cork or the like, having a pair of perforations corresponding to the perforations in the lamp front through which the glass member of this front is visible. The portion of the stencil plate 32 in which the letters 33 are punched is embossed forwardly of the lamp so as to compensate for the thickness of the packing, thereby permitting this portion to bear flatwise against the back of the corresponding lens portion 9 so as to insure a sharp definition of the outlines of the letters.

In practice, a firm fastening of the tubular rivets 25 which are disposed near the two lower corners of the stencil plate will tend to tilt the upper end of the stencil plate rearwardly or inwardly of the lamp and hence would bring the perforated part of this plate away from the adjacent lens portion. To overcome this I provide the upper portion of the stencil plate with a finger 36 projecting upwards sufficiently so that it will be interposed between the cork packing 34 and the flange 4 when the door is in position. With the stencil plate thus constructed, the securing of the lamp front to the body of the lamp by means of the cover holding screws 38 will cause the stencil plate to be pressed forwardly into tight engagement with the corresponding portion 9 of the glass front of the lamp, and the resiliency of the stencil plate in resisting this forward flexing affords a spring tension which prevents any jarring from loosening the cover holding screws 38.

However, while I have illustrated and described the lamp of my invention in an embodiment including various highly desirable features of construction and arrangement, I do not wish to be limited to these. Obviously, many changes might be made without departing either from the spirit of my

invention or from the appended claims, and some of the novel features of my invention might be employed independent of others. For example, instead of forming both lens portions of a single piece of glass, I may employ separate lenses 51 and 52 having outlines about as shown in dotted lines in Fig. 6, thereby permitting the use of different colors for the two lenses, in which case the central vertical cross-section of the lamp front or cover portion might be as shown in Fig. 9.

I claim as my invention:—

1. In a lamp, a forwardly open casing, a front having a pair of lens portions, a pair of lamp bulbs, means for supporting the lamp bulbs within the casing respectively back of the two lens portions, and a partition extending longitudinally of the casing between the lamp bulbs and having its main portion in a plane intersecting one of the said lens portions, the partition having a forward portion bowed out of the said plane to conform substantially to the adjacent peripheral part of the said intersected lens portion so as to enlarge the casing compartment opposite the last named lens portion.

2. In a lamp, a forwardly open casing, a front having a pair of lens portions, a pair of lamp bulbs, means for supporting the lamp bulbs within the casing respectively back of the two lens portions, and a partition extending longitudinally of the casing between the lamp bulbs and having its main portion in a plane intersecting one of the said lens portions, the partition having a forward portion bowed out of the said plane to conform substantially to the adjacent peripheral part of the said intersected lens portion so as to enlarge the casing compartment opposite the last named lens portion, the said bowed portion of the partition being inclined forwardly of the lamp so as to deflect rays of light from the lamp bulb opposite the said intersected lens portion through this lens portion.

3. In a lamp, a forwardly open casing, a front having a lower lens portion of upwardly convexed upper contour and an upper lens portion above the aforesaid lens portion, and a partition having the major part of its longitudinal medial portion in a surface intersecting the said upper contour of the lower lens, the partition having the forward part of its said medial portion arched upwardly to correspond substantially to the intersected lens contour portion.

4. In a lamp, a forwardly open casing, a front having a lower lens portion of upwardly convexed upper contour and an upper lens portion above the aforesaid lens portion, and a partition having the major part of its longitudinal medial portion in a surface intersecting the said upper contour of the lower lens, the partition having the

forward part of its said medial portion arched upwardly to correspond substantially to the intersected lens contour portion, the said arched partition part being forwardly 5 and downwardly convexed in a section longitudinal of the lamp.

5. In a lamp, a forwardly open casing, a lamp front having upper and lower lens portions, a partition extending longitudinally 10 of the lamp to divide the latter into two compartments respectively opposite the two lens portions, a lamp bulb mounted in the lower compartment, and a second lamp bulb having its base supported by the partition 15 and its filament disposed in the upper compartment, the lamp-base-supporting part of the partition being depressed below the top of the lower lens to permit the insertion of a relatively tall lamp bulb into the upper 20 compartment, the partition having the part forwardly of its said lamp-base supporting portion bowed upwardly to present the entire height of the lower lens opposite the lower compartment.

25 6. In a lamp having a forwardly open casing divided by a partition into upper and lower compartments, a substantially central depression in the partition, a lamp-socket having its shell projecting downwardly

from the central depressed part of the partition and provided with means for receiving the base of a lamp bulb inserted into the upper compartment of the lamp, the said depression of the partition and the downward disposition of the socket cooperating 30 to permit the use of a relatively tall lamp bulb in the upper compartment.

7. In a lamp having a forwardly open casing divided by a partition into upper and lower compartments, a substantially central 40 depression in the partition, a lamp-socket having its shell projecting downwardly from the central depressed part of the partition and provided with means for receiving the base of a lamp bulb inserted into the 45 upper compartment of the lamp, the said depression of the partition and the downward disposition of the socket cooperating to permit the use of a relatively tall lamp bulb in the upper compartment, the partition having the forward part of its depressed portion inclined upwardly toward the front of the lamp to increase the effective height of the lower compartment forwardly of the 50 said socket.

Signed at Detroit, Michigan, June 12, 55
1924.

CHARLES E. GODLEY.
